ATTORNEY.

UNITED STATES PATENT OFFICE.

ALBERT B. CLARK, OF HAMBURG, NEW YORK.

INVALID'S BED.

SPECIFICATION forming part of Letters Patent No. 653,440, dated July 10, 1900.

Application filed August 1, 1898, Serial No. 687,463. (No model.)

To all whom it may concern:

Be it known that I, ALBERT B. CLARK, a citizen of the United States, residing at Hamburg, in the county of Erie and State of New York, have invented certain new and useful Improvements in Invalids' Beds, of which the following is a specification.

My invention relates to improvements in fracture and invalids' cots; and the object is to provide a supplementary adjustable frame within the main bed-frame which can be easily raised to or lowered from the patient to allow the changing of bedclothes. It also relates to an adjustable pillow-frame, the mechanism employed to raise and lower the adjustable bed-frame, and the mechanism employed to operate the adjustable pillow, all of which will be fully and clearly herein-after described and claimed, reference being had to the accompanying drawings, in which—

Figure 1 represents a side elevation of my improved bedstead. Fig. 2 represents a front view of the same. Fig. 3 represents a rear view of the bedstead. Fig. 4 represents a detached view of a portion of the footboard, illustrating the means employed to lock the elevating mechanism. Fig. 5 represents a detached view of the cross-bar at the head of the bed, showing the construction of the cog mechanism employed to elevate the supplementary frame. Fig. 6 represents a section through a portion of the frame on line *a a*, Fig. 2, to illustrate the slideway in the main frame. Fig. 7 is an enlarged transverse section through the canvas-supporting tubes and the canvas on or about line *b b*, Fig. 1.

In referring to the drawings in detail like numerals represent like parts.

The main frame proper is composed of side bars 1, the head comprising the front substantially-vertical bars 2 and 3, the head-board 4, which joins the tops of the bars 2 and 3, the middle cross-bar 5, and the lower cross-bar 6, and the foot comprising the substantially-vertical bars 7, which are duplicates and therefore denoted by the same numeral, and the upper middle and bottom horizontal cross-bars 8, 9, and 10, and the central vertical brace or bar 19. The substantially-ver-

tical bars 2, 3, and 7 are provided with longitudinal grooves 11, forming slideways, and

the supplementary adjustable frame 12 is provided with extensions 13, fitting in said slideways. To elevate and lower the adjustable frame, 55 a toothed bar 14 is secured to said frame by means of the brace 15, and a shaft 15^a extends the entire length of the bed, with its ends supported in the middle cross-braces of the head and foot of the bed, respectively. 60 Upon the shaft are rigidly secured cog-wheels 16, which are adapted to mesh with the toothed bars 14, substantially as shown in Fig. 5. A ratchet-wheel 17 is also rigidly mounted upon the shaft, at or near each end 65 thereof, and pawls 18, pivotally mounted upon the cross-bars, are adapted to engage with the ratchet-wheels to prevent the rotation of the shaft in one direction. Two of the toothed bars and the cog-wheels are employed—one 70 set at each end of the frame—and both cog-wheels are rigidly mounted upon the shaft and are of substantially the same size, thus providing means for lifting both ends of the adjustable supplementary frame equally, the 75 rear set being preferably arranged directly in front of the central vertical brace 19. The vertical bars are provided with holes through which horizontal tubular bars 20, preferably formed of gas-pipe, are passed and secured 80 in place by means of the nuts 21. Between these tubes is supported an upper bed portion of canvas 22 or similar material, the canvas being provided with looped sides 23, through which the tubes 20 are passed. (See 85 Fig. 7.) An adjustable pillow-frame 24 is also provided, the bent ends 25 of the frame being pivotally secured to the horizontal tubes 20 by springing them into openings into the tubes, substantially as shown in Fig. 7. The 90 pillow-frame is also provided with a covering of canvas or similar material 25^a. A rod 26, having a forked upper end each of the branches of which is secured to the pillow-frame, is used to adjust the position of the 95 same, a rope 28 being attached at its lower end to the lower extreme of the forked rod, then passed over a pulley 29, and secured at its opposite end to a lever 30, pivoted at one extreme to the frame. To lock the lever in 100 its position when the pillow-frame is adjusted at the right angle, a series of holes or open-

ings 31 are provided in the vertical bar 3, and a pin 32 is inserted in the nearest opening to limit the upward movement of the lever.

The raised position of the pillow-frame is shown by full lines.

The pulley 33 (shown in Fig. 3) is for supporting the weight generally used to hold fractured limbs in position.

With my improved bed the clothes can be easily changed without removing the patient from the bed by lowering the supplementary frame, removing and changing the clothes thereon, the canvas supporting the patient in the meanwhile, then elevating said frame to its former position, first placing a clean canvas over the clean clothes, removing the bars from the loops in the soiled canvas and inserting them in the loops in the clean canvas, and also removing the soiled canvas by pulling it from under the patient.

I claim as my invention—

A bed for invalids, &c., comprising a main

frame having one of its vertical posts provided with a series of holes or openings a supplementary adjustable frame mounted on said main frame, means for raising and lowering said frame, an adjustable pillow-support in the form of a frame with its ends bent at substantially right angles and pivoted to the bed-frame; said pillow-support having adjustment independent of the adjustment of the supplementary frame, an arm having a forked end connected to said pillow-support, a lever pivoted to the bed so as to have a vertical movement upon said pivot, a rope extending from said lever to the lower portion of said forked arm, and a pin adapted to fit into any one of the holes in the frame-post to support the lever in any position to which it may be adjusted, as set forth.

ALBERT B. CLARK.
